METHOD OF MAKING, PACKING, AND SEALING CARTRIDGE CONTAINERS

August G. Liebmann, Washington, D. C., assignor of one-half to Harry A. Blessing, Washington, D. C.

Application June 18, 1943, Serial No. 491,364

7 Claims.

(Cl. 93—3)

The present invention relates to improved methods of making, packing and sealing cartridge containers. These containers fabricated from paper or cellulose materials, such types of receptacles particularly though not exclusively, cylindrical in form and especially those adapted to be used for packaging of foods and more especially foods having dehydrated characteristics.

The primary object of the present invention is to provide a simple, effective, and economical method for making, packing, and sealing containers of this type.

A further object of the invention is to make, charge and seal such containers with substantially no waste of materials in the operation of the same.

Reference being made to the accompanying drawings describing the invention, attention is directed to the copending applications Serial No. 449,949, filed July 6, 1942, and also Serial No. 472,640, filed January 16, 1943, the former is hereinafter referred to as the primary unit and the latter as the secondary unit.

The process of fabricating pieces of tubing for making containers being disclosed in the aforesaid units, the present invention disclosing the method of using such fabricated materials and packaging the products to be handled.

In the accompanying drawings—

Figure 1 is a cross section of the headblock of the primary unit taken on its vertical axis.

Figure 2 is a detail fragment of the shackle bar, with yokes fixed to the headblock guides, to prevent premature ejection of materials within an aperture of the headblock.

Figure 3 is a fragment of an adapter stop, the adaptor being a sleeve of variable thickness in gaging the aperture to compensate for different diameters of preformed tubing in the preparation of the container tubes.

Figure 3A is a cross section of the vertical axis of the bipartite headblock of the secondary unit, for forming flanges on inner tube.

Figure 4 is a fragmentary top plan view of Fig. 3A for forming flanges on the inner tube.

Figure 5 is a view in elevation of one of the male dies, with the female die shown in dotted lines, supplementary to Figure 3A.

Figure 6 is an end closure die for pressing or upsetting by deforming and making a flange on a preformed disk for a spacing end closure. The elements shown in Figure 5 with modification in degree and not in kind may be used substantially to cut discs for the end closure in blank 55

for outer or inner closures, flanged or unflanged, blanks.

Figure 7 is a top plan view of Figure 6.

Reference now being had to the numerals the headblock 1 is vertically movable in its guides 2; fixed to the guides are right and left crimping means 3. These are stationary and held by yokes not shown. These crimping means are composed of cylindrical housings 4 and provided with a rotary broach 5 which has a taper end 6 and a rotary crimping roller 7 piercing and held by the broach for rotary movement. As the broach rotates, the roller rotates through friction hold upon the end of the tube to be crimped. At the opposite end of the broach is a screw member 8 having an enlarged portion provided with ball or other anti-friction bearings 9, which is disposed between the taper end of the broach and the screw threaded portion of the same. An extension shank of the screw threaded portion is provided with a hand wheel 10 and crank effect 11 and as the screw threaded portion 8 works within the housing 4 the required leverage to iron down and inwardly the end of a tube is thus provided in this crimping means.

This consists of a broach 5 having a taper portion 3 at one end thereof, a threaded shank 8 at the opposite end thereof; an enlarged portion or bearing 9, mounted for reciprocal movement in a housing 4; the taper portion of the broach 3 adapted to rotate within the end of tubular material to be crimped; a spindle 1 pierces the broach and is mounted at right angles to the axis of the broach. The spindle 1 rotates with the axis of the broach 5 but on engagement with the end of tubular stock, it also rotates upon its own axis, as well as that of the broach by which it is carried. The broach being arranged to feed toward the work, in such a way as to enter the end of a tube, and by virtue of the geometrical shape of the tube, circular, and the taper of the broach, the inclination of the end of the tube to bend inwardly owing to its geometrical form, is furthered by the spindle grooves pressing upon the end in such a manner as to infold the end of the tube and against the taper portion of the broach which irons or crimps the same inwardly.

The crimping head, with the screw and broach rotates upon its axis; and the spindle rotates with it in the same orbital or rotary movement.

The spindle of the crimping means rotates in idling as above noted, but in addition thereto it rotates upon its own axis as well as the aforementioned, when in contact with the work.

Disposed within an aperture of the headblock

and designated by numeral 12 is the cylindrical adapter, provided with a stop at one end of the same which is a swinging disc 13 secured open or shut by a thumb screw. This stop 13 is adapted to control the passage of tubes as cut off passing through the adapter and to be passed to the secondary unit for the flanging operation of the ends of same which is more fully and hereinafter described.

The ramrod 16, Fig. 1, registers with an aperture of the headblock when brought in registry therewith, and disposed in the said aperture at its greatest diameter is a piece of tubing 17 the outer tube which is held from premature ejection by means of the slidably mounted shackle bar 18 carried by the yokes 19.

Disposed opposite to the adapter is a piece of tubing shown in section designated 16 and within the adapter a piece of tubing (cut off) 15, to be relayed to the secondary unit for deforming flanges thereon. Disposed within the piece of tubing 17 opposite the ramrod 16 is the deformed inner tube having flanges, known as the inner tube 22 also charged with product, and having end closures 20 and 21 at its ends ready to be moved upward to the crimping means and have the ends of the outer tube 17 folded inwardly and crimped thus sealing the encased elements and product therein contained.

The inner tube 22 is flanged or deformed on the secondary unit, as in Figures 3A, 4 and 5; the bipartite headblock 23 is composed of right and left sections laterally shiftable to open and close upon tubes for the flanging operation, designated 22, the headblock 23 is shifted in guides coaxing with shoes 24 by means of the pistons 25 and the male dies 26 with extensions 27 deform the ends of the tube of the bipartite headblock which is in effect the female die. In Figures 6 and 7, Figure 6 a vertical axis cross section of the bipartite headblock shows the headblock 23, the female die 28 carried by the bipartite headblock 23 in which the disc 30 is deformed by pressure from the male die 29 upon the disc 30 within the female die 28, thus forming a flange, by deformation of a flat disc.

The ejector rod 31 is utilized to eject the flanged disc 30 from the female die 28.

The tolerance of difference in diameters of the inner and outer tubes fabricated into interfitting relationship are compensated by the arrangement and dimensions of apertures in the headblock of the primary unit and in the dies carried by the bipartite headblock. Figure 3a discloses the male die 13 cooperating with the plunger and female die 12 held by the bipartite headblock for upsetting or deforming the ends of an open end piece of tubing. In passing from the primary unit to the secondary unit by way of the rotary conveyor, the ends of this piece of tubing to be deformed are wetted in hot paraffin, this serves a dual purpose:

(1) Prevents splaying of the ends during the deforming operation. (2) Impregnates the surfaces in slidable contact when force fitted into the interior of the outer tube, thus acting as a lubricant for that purpose.

While not so essential in deforming other parts, such as flanging the edges of the discs for the end closures, it may be also used with substantially heavy stock for this purpose and as such wetted surface does not come into contact with the contents nor has any intercommunication

therewith, the hygroscopic effect of such wetting is thereby avoided, as it is limited to the dead air spaces between the walls of the container.

What is claimed as new is:

5 1. The method of fabricating insulated cartridge containers; forming circumferential flanges on the ends of a tubular member; forming peripheral flanges on closure disk members; stuffing the flanged tubular member; pressing 10 the filled tubular member into another tubular member; inserting the peripherally-flanged closure disks; inserting other closure disks thereover and crimping the ends of the second tubular member over the second closure disks, substantially as described.

15 2. The method of fabricating insulated cartridge containers; forming circumferential flanges on the ends of a tubular member; forming peripheral flanges on closure disk members; 20 stuffing the flanged tubular member; pressing the filled, tubular member into another tubular member; inserting the peripherally-flanged closure disks; inserting other closure disks thereover and crimping the ends of the second tubular member over the second closure disks, by means of a rotary crimping head.

25 3. The method of fabricating insulated cartridge containers; flanging the ends of tubular members; flanging the edges of closure disk 30 members; charging the flanged tubular member; pressing the charged tubular member into another tubular member; inserting the flange-edge disks; inserting other closure disks thereover and inturning the ends of the second tubular member 35 over the second closure disks.

40 4. The method of fabricating insulated cartridge containers; flanging the ends of tubular members; flanging the edges of closure disks, to effect dishes; charging the flanged tubular member; pressing the charged tubular member into another tubular member; inserting the dishes; inserting other closure disks thereover and inturning the ends of the second tubular member over the second closure disks.

45 5. The method of fabricating insulated cartridge containers; flanging the ends of tubular members, making dishes from disks; charging the flanged tubular member; pressing the charged tubular member into another tubular member; inserting the dishes, inserting disks upon the dishes and inturning the ends of the second tubular member over the second closure disks.

55 6. The method of fabricating insulated cartridge containers; flanging the ends of tubular members; forming dishes from disks; stuffing the flanged tubular member; compressing the stuffed tubular member by encasement within another tubular member; inserting the dishes; 60 inserting disks upon the dishes; and crimping the ends of the second tubular member over the disks.

65 7. The method of making, packing and sealing cartridge containers of the insulated type; flanging the ends of tubular members; forming dishes from disks; stuffing the flanged tubular member; encasing the stuffed tubular member within another tubular member; inserting the dishes; inserting disks upon the dishes; and crimping the 70 ends of the second tubular member over the disks.

AUGUST G. LIEBMAN.
